(57) **CLAIM**

The ornamental design for a fastening device, as shown and described.

DESCRIPTION

FIG. 1 is a perspective view of the fastening device showing my new and ornamental design in a closed configuration; FIG. 2 is a front view thereof;

FIG. 3 is a rear side view thereof;

FIG. 4 is a left side view thereof;

FIG. 5 is a right side view thereof;

FIG. 6 is a top side view thereof;

FIG. 7 is a bottom view thereof;

FIG. 8 is a perspective view of the fastening device of FIG. 1, showing my new and ornamental design in an open configuration;

FIG. 9 is a front view thereof;

FIG. 10 is a rear side view thereof;

FIG. 11 is a left side view thereof;

FIG. 12 is a right side view thereof;

FIG. 13 is a top side view thereof; and,

FIG. 14 is a bottom view thereof.

The broken lines in the drawings illustrate portions of the fastening device and form no part of the claimed design.

1 Claim, 13 Drawing Sheets
